J. A. TAYLOR.
BRACE FOR RIVET DRIVING TOOLS.
FILED NOV. 8, 1918.

James A. Taylor

INVENTOR.

UNITED STATES PATENT OFFICE.

JAMES A. TAYLOR, OF GLEN RIDGE BOROUGH, NEW JERSEY.

BRACE FOR RIVET-DRIVING TOOLS.

Application filed November 8, 1918. Serial No. 261,703.

To all whom it may concern:

Be it known that I, JAMES A. TAYLOR, a citizen of the United States, residing at the borough of Glen Ridge, county of Essex, State of New Jersey, have invented new and useful Improvements in Braces for Rivet-Driving Tools, of which the following is a specification.

Riveting with automatic tools, as at present conducted, requires great strength and skill and the constant jarring and vibration produce mental and physical fatigue that militates against efficient and continued labor.

The objects of my invention are to provide a device which will aid in all the operations of driving rivets by providing a mechanical brace for the rivet driving tool which will relieve the operator of the jar and back pressure of the instrument while in operation and at the same time provide means for freely changing the position of the tool while the length of the rivet is being decreased by the blows from the tool and also for changing the direction of the blow, especially when the rivet has been hammered down to the unshaped head stage and it is desired to flatten and round off the same into its finished form. The interposition of this brace conserves the full force of the blow which is struck upon the rivet solidly and without perceptible yielding of the brace and the tool. The device is of such form that when the same has been secured to the plates which are to be riveted together a great number of rivets may be driven by merely sliding the part that supports and braces the tool itself along a support bar or by adjusting the bar itself without loosening the whole device from the plates.

To such ends my said invention, in its preferred form consists of a brace bar attached by adjustable plugs to the material to be riveted, a movable collar mounted on this brace bar provided with a socket into which fits a brace part fastened immovably to the riveting tool having a convex upper face concentric with the face of the socket, and means for raising this socket and the tool as may be desired. The face of the socket and the face of the tool collar are arcs of a circle whose center is the head of the rivet. Since the socket is in the form of a rim with the top and the bottom open the tool may oscillate in the socket while the hammering end of the same is kept constantly on the

rivet head. A second brace bar is provided and is movably attached by a sliding collar and set screw to the first brace bar to permit the moving of the bars over a field of rivet holes and thus enable the operator to rivet a large number of rivets without removing the entire device from the plates which are to be riveted together. The tool holding collar on the first brace bar is mounted so as to permit of movement back and forth over a field of rivets when the same are in a line parallel to the first brace bar. The device is secured to the material to be riveted together by adjustable plugs, all of which are mounted in slots so that the same may be adjusted with considerable latitude in rivet holes that are not in straight lines.

My said invention is fully shown described and claimed in the following specification of which the accompanying drawings form a part; wherein letters or numerals of reference designate like or equivalent parts wherever found throughout the several views and in which:

Figure 1 is a top view of the entire device, showing the rivet driving tool in position in the brace part which is mounted on the main brace bar, and both brace bars secured together and placed in their relation to the plate or material to be riveted and the rivet holes in the same.

Figure 2 is the top view of the movable collar supporting the rivet driving tool brace and showing in dotted lines the rotating ovoidal shaped cam part for changing the position of the rivet driving tool and its brace part during the process of driving a rivet.

Figure 3 is a side view in detail of the movable collar supporting the rivet driving tool brace, the rotating ovoidal shaped cam part for changing the position of the rivet driving tool brace, the rivet driving tool in position, the connecting bar for keeping the ovoidal shaped cam part and the rivet driving tool brace together during a change in position of both and the first brace bar in cross section, all of which are shown in relation to the material to be riveted together and to rivet to be driven.

Figure 4 is an end view in detail of the movable collar, the movable ovoidal shaped cam part, the rivet driving tool brace, the rod connecting the cam part and the tool brace, and showing in dotted lines the position taken by the last three when the cam

part is rotated and the tool brace and the tool are depressed to their lowest point.

Figure 5 is a side view in detail of the rivet driving tool brace with a portion of the brace in cross section along the line *a—a* of Figure 2.

Figure 6 is a side view of the rivet driving tool provided with an immovable brace part, the upper convex of which is a curve of the same radius as the curve of the face of the socket in the tool brace.

Figure 7 is a top view of the rivet driving tool provided with the immovable brace part.

Figure 8 is a side view of the second brace for carrying a movable collar through which also passes the first brace bar (shown in cross section), and by means of which collar and the set screw passing through its top wall the two brace bars are held together.

Figure 9 is a side view in detail of one of the securing plugs placed at the ends of the brace bars showing in dotted lines the dividing screw plug and the projecting part.

Figure 10 is a right side view of the securing plug with the dividing screw plug and the projecting part removed.

Figure 11 is a side view of the projecting part of the securing plug.

Referring to the drawing:

30 My said new and improved brace for rivet driving tools comprises a main brace bar A and a supplemental brace bar E, Figs. 1 and 8. On the brace bar A, Figs. 1 and 3 is mounted a sliding collar B which supports a brace C for the rivet driving tool D.

The tool brace C is movably mounted on the collar B by means of bar 1, Figs. 1, 2, 3, 4 and 5, passing through a hole in the collar B. The downward movement of the brace C is limited by the cap 2 on the bar 1. The outer end of the brace C, Figs. 1, 2, 3, 4, and 5 is in the form of a broken ring with the inner faces joining at an acute angle.

The aperture Y in the ring, Figs. 1 and 2 is of slightly greater width than the width of the shaft of the rivet driving tool D. The under face 3, Figs. 3, 4 and 5 of this ring is concave and in a uniform curve of the arc of a circle having a radius equal to the distance 50 from the top of the finished rivet to the face 3 when the brace C is in lowered position so as to permit the rivet driving tool D, Fig. 3 to be oscillated laterally with the top of the rivet as a center. The driving tool D, Figs. 53 and 6, is provided with a brace collar 4 in movably mounted thereon whose upper face 5 is concentric with the under face 3 of the brace C. The collar 4 is fixed on the tool at such a distance from the end thereof that the faces 3 and 5 abut when the brace C is in lowered position and the end of the tool is abutting against the head of the finished rivet, and the major portions of such faces will continue to abut throughout the limit of lateral motion of the tool D. The upper

inner face 6, Figs. 2, 3, 4 and 5 of the ring on the brace C is circular and at such an angle to the face 3 that it will be parallel to the sides of the shaft of the tool D when the latter is at the limit of its motion.

70 The brace C is provided with a strengthening part 7, Figs. 2, 3, 4 and 5, the inner face 8 of which, Figs. 2 and 3 abuts against the outer surface of the collar B. The part 7 serves to strengthen the brace C and to distribute the force of the blows of the rivet driving tool.

Loosely pivoted upon the end of the collar B by the bolt 9, Figs. 2, 3, and 4 is the cam part G having an egg or ovoidal shaped 80 perimeter, the horizontal diameter of which in the normal position is greater than the vertical diameter by slightly more than the height of the undriven rivet above the material to be riveted. The upper face of the part G abuts against the under face of a horizontal projection 11 on the collar B, Figs. 2, 3 and 4. The under face of the cam part G abuts against the upper face 12 of the brace C, Figs. 2, 3 and 4. Attached to the 90 cam part G, Figs. 2, 3 and 4 is a lever 13, which is held in a vertical position when the cam part G is in a normal position. When the lever 13, Fig. 4 is moved to the left and downward (as shown in dotted lines) the 95 cam part G is rotated on the pivot 9 and this rotation brings into contact with the face 12 of the brace C portions of the lower face of the cam part G which are continuously further and further removed from the pivot 9 100 and thus the brace C is forced downward until the point 14, Fig. 4 on the end of the cam part G is reached. The movement of the brace C is of such length that it will have reached its lowest point when the length of 105 the rivet has been decreased to such a stage that the head of the rivet is ready for finishing off and it is then desirable to provide for the lateral movement of the tool D for performing this process. During this movement, the lever 13 has been moved to its lowered position and consequently will not be in a position to interfere with the free lateral movement of the tool D.

110 The brace C and the cam part G are 115 loosely secured together by the slotted bar 15, Figs. 2, 3 and 4. The bar 15 is secured to the cam part G by the bolt 16 moving in the slot 17, Fig. 4, and to the brace C by the bolt 18. As the cam part G is rotated, the 120 bar 15 is moved to the right and the variation in the distance between the bolts 16 and 18 is permitted by reason of the bolt 16 moving in the slot 17. When the lever 13 and the cam part G are raised the bar 15 raises the 125 brace C and the brace C with the tool D is ready to be moved into position to perform the operation of driving another rivet.

The ends of the brace bars A and E are curved downward, Fig. 8, so as to elevate 130

the main portions of such bars to a suitable distance above the rivets to be driven and the material to be riveted together. The bars A and E are loosely held together, Figs. 5 1 and 8 by the slotted collar F. The slots of the collar F are of varying widths so as to permit the brace bars A and E to be turned at various angles to each other. The upper 10 and lower surfaces of the collar F are connected by posts 19, 20, 21 and 22. The posts 19 and 20 are closer together than 21 and 22 so that while the bar A may be turned at an angle to the bar F it is permitted practically no lateral movement. The bar E is provided 15 with a slot 10 in which the adjustable plug H may slide back and forth until the same is directly over a convenient rivet hole when it is firmly secured in place. The brace bar A is provided with a like slot at each end 20 and 32 which serve a like purpose. When the brace bars are in the desired position relative to each other they are secured in position by tightening the set screw 23, Figs. 1 and 8.

25 The brace bars A and E are secured to the material to be riveted by means of adjustable plugs H, H which are inserted in the empty rivet holes or convenient apertures in the material. One end of either 30 brace bar may be provided for convenience with a curved projection 24, Figs. 1 and 8, which may be inserted into a convenient rivet hole or aperture, or it may be provided with a similar adjustable plug H.

35 The adjustable plugs H, H, are inserted in the curved ends of the brace bar A at such equal distances from the body of the bar that a straight line may be drawn parallel to the body of the bar through their centers and 40 the center of the broken ring of the brace C, which is of such dimensions that its center will be directly over the center of the rivet to be driven. In practice, when riveting on flat horizontal surfaces, it may be 45 found convenient to use only the brace bar A and to omit the plugs H, H, in which case the bar will be held firmly against the material to be riveted together by heavy metal weights which fit over the ends of the bar 50 at the points where the plugs H, H are normally inserted. Such weights will be provided on their under surface with a short projecting part which will project into and through the slots 30 and 32 into convenient 55 rivet holes so as to hold the weights in place and prevent their movement through the vibration of the riveting tool.

60 The shaft 25, Figs. 9 and 10 of the adjustable plug H is provided at its lower end with a side projection 26, Figs. 9 and 10, slightly less in thickness than the width of a rivet hole in which a rivet of the kind to be driven is to be inserted. Inserted in a slot 27, Figs. 9 and 10, in the shaft of the 65 plug H is a movable projecting part 28,

Figs. 9 and 11, which is pivoted on the bolt 29 to the shaft 25. The shaft 25 is provided with a central threaded cavity, Figs. 9 and 10, into which is screwed a threaded spreader plunger 31, Fig. 9. The inner face of the 70 projection part 28 is threaded and projects into the bottom of the threaded cavity against which threaded face the lower or inclined threaded portion of the spreader plunger 31 abuts. In operation the shaft 75 of the plug H is inserted into the rivet hole until the projection 26 protrudes beyond the outer surface of the material to be riveted. When the plunger 31 is screwed down the threaded portion of the part 28 is forced 80 outward and as it abuts against the side of the rivet hole it forces the projection 26 beneath the surface of the material to be riveted and when all the plugs are adjusted the entire device is screwed firmly in place. 85 When the plunger 31 is unscrewed the part 28 is released and the plug H may be withdrawn. When all of the plugs have been withdrawn the entire device is released from the material. 90

The operation of my improved brace for rivet driving tools is as follows: The brace bars are secured in place by inserting the adjustable plugs H, H, into convenient rivet holes, screwing down the spreader plunger 95 31 and thus locking the plugs in position. The set screw 23 is now tightened, screwing the brace bars A and E firmly together. Since rivet holes are usually in straight lines and the plugs and the center of the rivet 100 driving tool brace are equidistant from the main part of the bar the rivet driving tool when in place will be directly above the rivet to be driven. The riveting tool is usually, though not necessarily held in the right 105 hand, inserted into the brace C by passing the shaft of the tool through the aperture Y in the ring, raising the tool until the brace on the tool abuts against the under surface of the ring 3. The tool is now ready for 110 operation. The lever, 13, usually, though not necessarily held in the left hand, is now pulled toward the operator and downward until the brace C, carrying the tool, is forced downward by the pressure of the curved face 115 of the cam part G against it, to a position in contact with the head of the rivet. As the rivet is hammered down the brace C is depressed so as to keep the rivet tool in proper contact with the rivet. When the rivet has 120 been hammered down sufficiently and it is desired to shape it into an appropriate "head" the handle of the tool is moved backward, forward and around. The brace on the tool and the under face of the brace 125 C being concentric, substantially equal contact is maintained and a solid brace provided at whatever angle the tool is held. In this way the head of the rivet may be tapered off to the desired angle. When the head of 130

the rivet has been finished the lever 13 is lifted, thus rotating the part G and lifting the brace C. The collar B is then pushed along the bar A until the rivet tool is directly over the next rivet and the operation is repeated.

Claims.

1. In a device of the class described, an elongated brace-bar; means for removably 10 securing each end of the brace-bar to the stock to be riveted; a sliding-collar centrally slidingly mounted upon the brace-bar between the end securing means; and means carried by the sliding-collar for supporting a 15 riveting or like tool-holder against back-pressure in such manner as to be universally rockable in the support.

2. In a device of the class described, an elongated brace-bar; means for removably 20 securing each end of the brace-bar to the stock to be riveted; a sliding-collar centrally slidingly mounted upon the brace-bar between the end securing means; and positively 25 acting means controlled by the operator, for advancing the immediate support of the tool, as the rivet is shortened in the operation of heading.

3. In a device of the character described, an elongated brace-bar having the end portions 30 extended from the main central portion of such brace-bar in one direction; means carried at each of such ends for removably securing each extended end to the stock to be riveted by co-action with rivet-holes 35 therein; a sliding-collar centrally slidingly mounted upon the brace-bar between such extended ends; and means carried by the sliding-collar for supporting a riveting or like tool-holder against back pressure in 40 such manner as to be universally rockable in the support; the construction and arrangement being such that the working portion of the tool will at all times be in line with the same line of rivet-holes axially coincident 45 with the holes by which such bar is secured by the extending end portions thereof.

4. In a device of the class described, a brace-bar; means carried at the ends of the brace-bar for removably securing the same 50 to the stock to be riveted by coaction with holes therein; a slide-member movably mounted on the brace-bar; a tool-carrier movable at substantially a right-angle to the axis of the brace-bar carried by the slide-member, having an annular tool-carrying collar provided with a slot for the reception and removal of the tool-housing, which collar is provided on the stock facing side with an annular concaved spheroido-segmental 55 shaped cavity surrounding the central orifice of the collar; a rivet-driving or heading-tool having a housing adapted to pass thru the collar-slot into the central collar orifice, provided with a convexed spheroido-segmental 60 back-pressure securing-disk fitting in 65

the coacting concave like shaped collar-cavity; and a manually actuated cam-member for gradually forcing the tool-carrier toward the adjacent stock-face as the rivet is shortened in the process of heading.

5. In a device of the class described, a brace-bar; means carried at the ends of the brace-bar for removably securing the same to the stock to be riveted by coaction with holes therein; an auxiliary brace-bar; an auxiliary slide-member movably mounted on such brace-bar and auxiliary brace-bar so as to slide upon one in one direction, and upon the other at an angle to the first direction across the first; securing-means carried by the auxiliary brace-bar, adjacent to the ends thereof, for removably securing the said auxiliary brace-bar to the stock by coaction with holes therein; a slide-member movably mounted on the brace-bar; a tool-carrier movable at substantially a right-angle to the axis of the brace-bar carried by the slide-member, having an annular tool-carrying collar provided with a slot for the reception and removal of the tool-housing, 80 which collar is provided on the stock-facing side with an annular concaved spheroidal-segmental shaped cavity surrounding the central orifice of the collar; a rivet-driving or heading-tool having a housing of such 85 diameter as to slip through the collar-slot into the central orifice, provided with a convexed spheroidal-segmental back-pressure securing-disk fitting in the coacting concave shaped collar-cavity; and a manually 90 controlled mechanism or member for gradually forcing the tool-carrier toward the adjacent stock-face as the rivet is gradually 95 shortened in the process of heading.

6. In a device of the class described, the 100 combination with a tool having a housing provided with an annular exteriorly extending convexed spheroidal-segmental shaped back-pressure securing-disk; of a movable support having a slotted collar one face of 105 which is provided with a concaved spheroidal-segmental cavity to receive the back-pressure securing-disk, the central orifice of the collar being of larger diameter than the exterior of the main-body portion of the 110 tool-housing to permit of universal rocking movement of the securing-disk in the cavity; a brace-bar movably supporting the movable support; and means carried by the brace-bar adjacent to the end for removably 115 securing the same to the stock to be riveted by coaction with holes therein.

7. In a device of the class described, the 120 combination with a tool having a housing provided with an annular exteriorly extending convexed spheroidal-segmental shaped back-pressure securing-disk; of a movable support having a slotted collar one face of 125 which is provided with a concaved spheroidal-segmental shaped cavity to receive the 130

back-pressure" securing-disk and retain the same in a universally rockable manner; a brace-bar slidably supporting the movable support thereon; means carried by the brace-bar for removably securing the same to the stock to be riveted by coaction with holes therein; and manually controlled mechanism for positively forcing the movable tool-support gradually toward the rivet as the same is gradually shortened in the process of heading.

8. In a device of the class described, a support for rivet-driving or heading-tools comprising a brace-bar; means for removably and temporarily securing the brace-bar at each end directly to the stock to be riveted by coaction with holes formed in and thru such stock; a tool-support movably supported by the brace-bar between the securing ends adapted to support the tool in a universally rockable position; and manually controlled mechanism for positively gradually forcing the tool-support toward the stock, as the rivet is shortened in the process of heading.

9. In a device of the class described, the combination with a brace-bar, of means for removably and temporarily securing the same directly to the stock to be riveted, com-

prising lug-bolts adapted to pass thru holes formed in and thru the stock and secured against displacement when in position by locking wedge-members, which lug-bolts are adapted to be attached to the brace-bar adjacent to its ends; a tool-support slidably supported by the brace-bar adapted to support the tool in a universally rockable manner against back-pressure; and mechanism carried by the tool-support, manually controlled, adapted to gradually and positively force the tool-support toward the stock being riveted, as the rivet is gradually shortened in the process of heading.

10. In a device of the class described, the combination with a brace-bar, of means for removably securing the same directly to the stock to be riveted, comprising lug-bolts adapted to pass thru holes formed in and thru the stock and secured against displacement when in position by locking wedge-members, which lug-bolts are adapted to be attached to the brace-bar adjacent to its ends; and a tool-support slidably mounted upon the brace-bar adapted to support the tool in a universally rockable manner against back-pressure.

JAMES A. TAYLOR.
